UNITED STATES PATENT OFFICE.

FRANK HEROT, OF CHICAGO, ILLINOIS.

COIN-CONTROLLED MECHANISM FOR VENDING MACHINES.

Application filed June 28, 1920. Serial No. 392,192.

To all whom it may concern:

Be it known that I, FRANK HEROT, a citizen of the United States, residing at Chicago, in the county of Cook and State of Illinois, have invented a new and useful Coin-Controlled Mechanism for Vending Machines, of which the following is a specification.

My invention relates to coin controlled mechanism for vending machines and it generically has for its purpose the provision of new and improved devices that are more especially designed for conveniently controlling the operation of a rotary shaft on which 10 the ejecting elements are mounted and held for engaging with the lowermost ones of packages contained in magazines or compartments from which they are to be vended.

My invention embodies generically an improved construction of coin controlled mechanism in which the use of springs is reduced to a single spring whose main function is to hold the rotary ejecting devices and the coin carrier that is loosely mounted 20 on the shaft, that carries the rotatable ejector devices, and which has peripheral pockets for edgewise receiving the inserted coins, in desired or normal position, and which also further serves as a means for applying a 25 knock or sudden impulse to the ejector devices, after they are turned a distance sufficient to eject the selected or purchased article and thereby operate for causing a positive and speedy ejection of the coin used for 30 connecting the movable parts during the operation of working the machine.

Again, my invention seeks to provide a simple, stable, and effective means for causing the deposited coin to interlockably connect the coin holder and the rotary shaft or goods ejector in such manner that a positive vending operation may be, at all times, effected after the proper coin has been inserted and danger of the coin slipping out of 40 position or the coin mechanism missing action, is positively overcome.

With other objects in view that will hereinafter appear, my invention embodies, in a coin controlled mechanism of the general 45 character stated, the peculiar features of construction and novel arrangement of parts, all of which will be hereinafter explained, specifically brought out in the appended claims and illustrated in the accompanying drawings, in which:

Figure 1 is a side elevation, parts being in section, of my improved coin controlled mechanism, so much of a vending machine structure being shown as is necessary to illustrate an operative and practical presentation of my invention. 60

Figure 2 is a rear end view of my improved coin controlled rotary ejector devices, the parts being in the normal position shown in Figure 1. 65

Figure 3 is a similar view of the other or front end of the said devices and illustrates a normal position of the coin receiving prongs and the cooperating gear-shaped coin receiver or holder. 70

Figure 4 is a similar view which illustrates the position of the coin when inserted for placing the coin mechanism in condition for rotating the ejector devices for delivery of an article. 75

Figure 5 is a front view of the coin holding gear and the pronged members that constitute a rigid part of the rotary ejector devices, the latter being indicated at the beginning of the goods discharging place and 80 the coin about to be thrown out of the coin holding parts, the position of the opposite or squared end of the rotary ejector devices and the coacting spring being indicated in dotted lines. 85

Figure 6 is a view similar to Figure 5 and shows the coin receiving gear and the forked coin holder at the coin ejecting position, the position of the opposite or squared end of the rotary ejector devices and the "knocker" 90 spring being indicated in dotted lines.

Figure 7 illustrates, in perspective, the multi-pronged coin engaged member that constitutes a part of the rotary ejector and the hand actuated gear shaped coin holder 95 and shifter hereinafter specifically referred to.

In the drawings, only so much of a goods holder is shown as is necessary to disclose a practical application of my invention and 100 in the said drawing, 1 designates the machine casing which is suitably provided, at its opposite sides, with bearings 2—2 upon which the goods ejecting means and the coin carrier 4 are operatively mounted in the 105 manner presently more fully explained.

A number of package holding magazines or chutes 5 are shown and they are arranged in parallel vertical alignment above the ejector elements and each chute 5 has a slotted 110

bottom 50 for the free rotation therethrough of the several ejecting members 8, of which four are shown arranged on quarters with respect to the shaft 23, so that as the shaft 5 is rocked a quarter turn, sufficient rotation is imparted to the ejector devices, when coin locked with the shaft, for discharging a package from one of the magazines, it being understood the ejectors, which may be of the 10 convenient form indicated, have their finger portions 80 so arranged that they engage the lowermost ones of the stacks of packages and discharge them laterally from the chutes or magazines 5 in the usual manner. In my 15 construction the ejectors 8 are all formed integrally with a long sleeve 81 that is journaled at the opposite ends in the opposite bearings 2-2 on the inside of the casing end and in which the operating shaft 9 is 20 loosely mounted. The front end of the shaft 9 has a socket 20, the purpose of which will presently appear.

At the inner end, the sleeve 81 has the usual integral squared head 82 which is engaged by the free end of a flat spring 10 that is secured to the casing wall, in any suitable way, so that its front or free end, at all times, rests upon one of the flat edges of the head 82 and thereby holds the ejector sleeve and its ejector members, at all times, in proper position for operation.

At the front or outer end, the sleeve 81 has a spider in the nature of four equi-distantly spaced members 84, each of which 35 has a bifurcated angled finger 83.

In the practical assemblage of the several parts mentioned, the bifurcated fingers 83 are positioned for being turned in line with the lower or delivery end of the coin chute 40 and, as is clearly indicated in Figure 1, it will be noticed the several fingers 84 also project over the coin carrier into which the coins are received as they drop down the coin chute and through any one of the fingers 83 that may be turned to register with the coin chute as before mentioned.

The coin carrier, in my construction, is in the nature of a gear wheel having closely related cog-like teeth, the teeth being separated at the innermost point to constitute 50 pockets 13 of sufficient width to snugly receive and hold the coins edgewise therein when they drop through the slotted finger 83 which is in line with the coin delivery chute.

The gear-like carrier is fixedly secured, by a screw pin 14 onto a hub-like sleeve that passes through the outer casing wall and fits onto the adjacent end of the shaft 9 which supports the rotatable ejector devices, as shown.

The screw pin 14 passes through the sleeve 15 and engages the socket 20 in the shaft and thereby locks the coin holder 4-4 and the operating crank or knob 16 and the 65 shaft to turn together.

So long as there is no coin in place, the knob may be freely turned in either direction to bring the forked member 84 in proper position for edgewise receiving the coin dropped through the coin chute. After the coin has 70 been dropped and it sets edgewise on one of the gear-like pockets of the carrier and through one of the prong fingers 83, it now locks the shaft 9 and the ejector devices to move together. As the ejector is turned to 75 discharge the match box, the flat spring that engages the squared end member of the rear end of the shaft, gathers tension as one of the corner edges of the square shaped member or head lifts the spring 10 that lays 80 edgewise on the squared or flat edge of the said member.

When the shaft 9, with its member 84 has been turned to the point of discharging the purchased box, or other article being vended, 85 and the flat spring passes over the approaching corner of the member 82, the stored tension of the spring causes its front end to snap down with force against the next advancing flat edge of the member 82, thereby 90 giving the member 82 on the shaft 1, on which the coin carrier is fixedly held, a sudden knock that causes it to turn quickly forward and in doing so causes the coin to drop out of engagement with the carrier and the 95 forked member and to facilitate the drop of the coin at the proper time, that is, when the shaft is knocked or jolted by the spring, as stated. The several pockets in the carrier are cut at an angle, as indicated at 25, to 100 produce bevelled surfaces that incline toward the forwardly going direction of the carrier which gives the coin sufficient play and prevents it from binding or sticking in the coin pockets.

My invention is of a very simple and inexpensive character, the ejecting devices and the coin controlled members being so arranged that my said coin controlled mechanism may be readily applied to any of the 110 many types of vending machines in which a revoluble ejecting device is utilized for discharging the goods.

What I claim is:

1. In a coin controlled vending machine, 115 a hand operated member, a good ejecting device normally disconnected from the hand operated member but adapted to be operatively connected therewith through the medium of the deposited coin, the said hand operated member including a gear shaped coin holder, the goods ejecting member having a disk with at least one slotted finger projecting laterally therefrom with which the deposited coin engages as it drops edgewise into the coin receiver, and means for imparting a jar to the ejecting devices as they reach the goods delivery position whereby to positively separate the coin from the coin carrier and the slotted finger. 120 125 130

2. In a coin controlled vending machine, a hand operated rotary shaft, a rotary goods ejector loosely mounted on the shaft, a squared head on one end of the ejector, a 5 spider on the other end of the ejector having slotted angled fingers, one of which corresponds to each side of the squared head, the several slotted fingers being disposed in longitudinal alignment with the four corners of 10 the squared head, a spring engaging the head and adapted for imparting quick forward impulses to the head as the corners thereof pass from under it, a gear that rotates within the confines of the slotted fingers of the ejector whereby the deposited 15 coin can pass edgewise through a selected one of the slotted fingers and into one of the spaces between adjacent teeth of the gear for locking the hand operated shaft and the 20 ejector to turn together.
3. In a coin controlled vending machine, a hand operated rotary shaft, a rotary goods ejector loosely mounted on the shaft, a squared head on one end of the ejector, a 25 spider on the other end of the ejector having slotted angled fingers, one of which corresponds to each side of the squared head, the several slotted fingers being disposed in longitudinal alignment with the four corners 30 of the squared head, a spring engaging the head and adapted for imparting quick forward impulses to the head as the corners thereof pass from under it, a disk having radial cross grooves in its peripheral edge 35 that rotates within the confines of the slotted
4. In a coin controlled vending machine, a hand operated rotatably mounted shaft, a second member including a sleeve loosely mounted on the shaft and having at least one ejecting extension adapted for engaging a package to be discharged, said sleeve having a cam-like member including at least one edge and cooperative flat bearing surface, a fixedly held flat spring whose outer free end 40 engages the cam edge or surface and tends to impart a jerky rotation to the sleeve on the shaft, a turning hub and a receiver having radial grooves for edgewise holding a coin, means for fixedly holding the hub and coin receiver to turn with the shaft, at least 45 one radially projected member on the rotatable sleeve having a bifurcated angular finger in which the coin is held as it edgewise rests in one of the radial grooves of the receiver, one wall of each of the coin grooves 50 in the receiver being outwardly bevelled whereby to provide lateral play of the coin, as the receiver and the forked finger are turned, to the coin discharging position. 55

FRANK HEROT.
